UNITED STATES PATENT OFFICE.

GOLDSBURY H. POND, OF NEW YORK, N. Y., ASSIGNOR TO HATTIE M. POND,
OF ASHBURNHAM, MASSACHUSETTS.

STEAM-BOILER.

SPECIFICATION forming part of Letters Patent No. 245,400, dated August 9, 1881.

Application filed October 9, 1880. (No model.)

To all whom it may concern:

Be it known that I, GOLDSBURY H. POND, a citizen of the United States, residing at New York city, in the county and State of New York, have invented certain new and useful 5 Improvements in Steam-Boilers, of which the following is a specification.

My invention consists in forming boiler-sections by uniting two sets of upright tubes, one 10 located concentrically within the other, with two horizontal tubes, one at each end of the upright set of double tubes, the horizontal tubes projecting beyond the furnace-casing, the upper horizontal tubes connected with a 15 steam-drum outside of the furnace-casing, said connections serving to retain the outer set of tubes in position, and the end of the lower horizontal tube connected with a water-drum, also located outside the furnace-casing, the 20 said section having a disk placed in the passage between the steam-drum and each section, said disk being perforated with one or more holes for the steam to pass through to the steam-drum, for the purpose of regulating 25 the amount of steam drawn from each section to prevent exhausting the steam in a section and sucking the water up into the steam-drum, usually called "flooding" or "foaming," and which occurs when the throttle-valve is sud- 30 denly thrown wide open.

The object of my invention is to simplify construction, to avoid joints, bolts, or seams in that part of the boiler that comes in contact with the fire, entirely overcoming the 35 cause of leakage from contact of joints with fire; also, to regulate the flow of steam from each section independent of the other, for the purpose of preventing flooding or foaming. I attain these objects by the mechanism illustrated by the accompanying drawings, in 40 which—

Figure 1 is a side elevation of my improved boiler, a portion of the upper horizontal pipe broken away to show the disk for regulating 45 the flow of steam from the section to the steam-drum. Fig. 2 is the steam-drum. Fig. 3 is an end view of the sections before the steam and water drums are attached. Fig. 4 is the wa-

ter-drum. Fig. 5 is the perforated regulating-disk. Fig. 6 shows a perspective view of my 50 improved boiler, representing a front and side elevation, the casing being removed. Fig. 7 shows a front elevation with one section of the boiler in place. This figure also shows the sectional detail composing the different sets of 55 tubes and their mode of fastening.

A is the main upright water-tube. B is the small or fire tube within it. C is the horizontal tube at the top. D is the lower horizontal tube. E is the steam-drum. F is the water-drum. 60 G is the perforated regulating-disk for controlling the flow of steam from each section to the steam-drum.

The drums E and F are coupled to the projecting ends of the horizontal tubes of the sections outside of the walls of the fire-space, so that the joints do not come in contact with the fire. The joints are made by means of the flanges H and I, which are held together by 65 any suitable means.

The disk G is held in place by being properly fitted and then driven in flush with the flange. The flange of the steam-drum, being a little smaller, holds it in place.

Having described my invention, what I claim 75 as new is—

1. A steam-boiler the sections of which are formed by a double set of perpendicular tubes, one set located concentrically within the other, and these connected at each end with horizontal tubes, the said horizontal tubes projecting beyond the wall of the fire-space, the upper ones connected to a steam-drum, and having interposed between the joints a perforated separating-disk, and the lower one connected 85 with a water-drum, also outside the wall of the fire-space, substantially as and for the purpose set forth.

2. A steam-boiler provided with a perforated disk to partly close the opening from 90 each section to the steam-drum for the purpose of regulating the flow of steam from the sections to the steam-drum, and to prevent the drawing up of water and flooding the steam pipe and engine, combined and arranged sub- 95 substantially as and for the purpose set forth.

3. A sectional steam-boiler composed of a double set of vertical tubes, A and B, one set within the other, the ends of said tubes being secured to a third set, C D, arranged horizontally, one below and one above, the horizontal set being secured to a fourth set outside of the fire-space, the upper and steam receiving sec-

tions being provided with a perforated separating-disk, substantially as and for the purpose set forth.

GOLDSBURY H. POND.
